UNITED STATES PATENT OFFICE.

CLINTON A. TEFFT, OF GLOVERSVILLE, NEW YORK.

AEROPLANE.

1,196,493.

Specification of Letters Patent. Patented Aug. 29, 1916.

Application filed April 22, 1916. Serial No. 93,014.

To all whom it may concern:

Be it known that I, CLINTON A. TEFFT, a citizen of the United States, and a resident of Gloversville, in the county of Fulton and State of New York, have invented a new and Improved Aeroplane, of which the following is a full, clear, and exact description.

This invention relates to airships and particularly to an airship which combines the buoyancy of a dirigible balloon and the characteristics of an aeroplane.

The object in view is to provide an improved construction which will be safe in use and which will have a large carrying capacity without straining any parts of the machine.

Another object in view is to provide a construction which will have substantially the speed of an aeroplane and the usual characteristics of such a machine, and in addition the buoyancy which will prevent falling in case of trouble with the engine or other parts of the machine.

A still further object in view is to provide an aeroplane construction with hollow planes merging into a substantially tubular body extending an appreciable distance to the rear, the hollow part of the planes and the body being arranged to receive a light gas for producing a buoyant effect.

In the accompanying drawings: Figure 1 is a side view of a device embodying the invention, certain parts being broken away for better illustrating the construction.

Fig. 2 is a top plan view of the structure shown in Fig. 1, part being broken away for showing the interior structure of certain parts of the machine. Fig. 3 is a front view of the structure shown in Fig. 1. Fig. 4 is a rear view of the structure shown in Fig. 1.

Referring to the accompanying drawings by numerals, 1 indicates the body of the machine to which suitable traction and supporting means 2 are secured, said traction and supporting means including suitable braces and also wheels. Associated with the body 1 is a driving engine and other usual parts of an aeroplane whereby the propeller 3 is rotated and the steering mechanism is operated, these parts, however, not being shown as the detail structure thereof forms no part of the present invention. In connection with the steering mechanism it may be stated that instead of having the conventional steering now commonly in use the steering mechanism is connected with the

rudder 4 for steering the aeroplane laterally or in a horizontal plane, and also connected to the plane or rudder 5 for steering up and down.

The frame 1 may be of any suitable structure and may be inclosed if desired, the same being connected to a lifting plane 6 which extends an appreciable distance on each side of the frame 1, as shown in Fig. 2, 60 said lifting plane being formed of the usual shape on the lower side while the upper side is rounded so as to produce an open chamber in which gas may be inserted. Suitable braces 7 may be provided for holding or supporting the covering, which covering may be of any suitable material, as for instance, sheet aluminum. Connected with the lifting plane 6 is a tubular member 8 which is normally held in a certain position by suitable ribs 9 and which is designed to receive a light gas so as to produce a buoyant effect for assisting the buoyant effect produced by the light gas in the lifting plane. The lifting plane 6 and the tubular member 8 may be connected up so that the gases will mix or may be divided as preferred so that in case one part gets punctured the other part will still be retained.

The member 8 is rounded and constructed substantially on the stream line effect, and the enlarged part of the plane 6 is arranged almost directly in back of the operating face when the machine is in use so that there will be little additional resistance to the air caused by the use of these members which carry the lifting gas. These members are not collapsible but are maintained in their position by the ribs 7 and 9 and other bracing members if the same are found necessary. Of course, the device may be made of any size and the width of the lifting plane 6 may be varied as desired as well as member 8, but it is desirable to have these members sufficiently large to contain a light gas of sufficient volume to support the device together with the pilot in the air in case the engine should break down or any other similar accident should occur, thus preventing a fall.

In operation, when it is desired to use the aeroplane hydrogen or other light gas is forced into the lifting plane 6 and also into member 8 until the proper quantity has been inserted. This will produce a buoyant effect and if these members are of sufficient size it will cause the machine to rise unless an

chored or provided with a load. Preferably the parts are so proportioned as to cause the device to remain suspended in the air with one of two persons thereon whereby the forward movement and the lifting of any additional load would necessitate the operation of the engine in the usual manner. If desired, a small gas manufacturing device could be carried for producing gas to take up any small leakage. In the practical operation of the device it is aimed to maintain the engine and other parts in proper condition for operation and also to maintain the gas in the lifting plane and member 8. If for any reason the engine and associated parts get out of order the device could not fall and will either remain in the air or will gradually descend. If there is enough gas to hold the device in the air the repairs can be made while in the air. After the repairs are made a landing is also made as quickly as possible and the complete permanent repairs provided for before further use of the device. In case the gas should escape by reason of part of the envelop becoming torn or otherwise, the device would remain suspended by reason of the aeroplane structure, but a landing is preferably made as soon as possible in order to repair the parts and provide for a new supply of lifting gas. In this way the aviator and passengers will be reasonably secure against accident, as two independent means are provided for maintaining the device in the air and when either device has become inoperative the other de-

vice is utilized for making the landing in safety.

What I claim is:

1. In an aeroplane of the character described, a lifting plane formed with an upper and lower face, said upper face diverging toward the rear from the lower face whereby a comparatively large space is produced between said faces designed to receive a lifting gas, and a container extending rearwardly from said lifting plane, the top and bottom walls of which merge into the upper and lower faces, respectively, of said lifting plane, said container being arranged to receive a lifting gas whereby the aeroplane is given a certain buoyancy. 40 45 50
2. In an aeroplane of the character described, a lifting plane formed of two wings, each of said wings having a lower lifting face and an upper covering face, the upper covering face merging at the center, said upper covering face diverging from the lower lifting face so as to produce a chamber extending from the tip of one wing to the tip of the other, said chamber being adapted to receive a lifting gas, and a tubular member merging into said planes at the point of juncture, said tubular member being adapted to receive lifting gas so as to assist in producing a buoyant effect in the aeroplane. 60 65
